J. Robinson,

Rotary Steam Engine.

No 15,667.

Patented Sep. 2, 1856.

UNITED STATES PATENT OFFICE.

JOHN ROBINGSON, OF NEW BRIGHTON, PENNSYLVANIA.

ROTARY STEAM-ENGINE.

Specification of Letters Patent No. 15,667, dated September 2, 1856.

To all whom it may concern:

Be it known that I, JOHN ROBINGSON, of New Brighton, in the county of Beaver and State of Pennsylvania, have invented a new and useful Improvement in Rotary Engines to be Impelled by Steam or other Fluid; and I do hereby declare that the following is a full, clear, and exact description of the same, reference being had to the accompanying drawings, forming part of this specification, in which—

Figure 1, is a vertical section taken perpendicularly to the axis of an engine constructed according to my invention. Fig. 2, is a vertical section of the same, parallel with the shaft. Fig. 3, is a side view of the piston head, supposed to be seen looking in the same direction as at Fig. 2.

Similar letters of reference indicate corresponding parts in both figures.

This invention relates to rotary engines, having a piston which is fixed relatively to the rotating shaft or only to a slight extent yielding, and sliding abutments. The improvement consists in a certain novel arrangement of induction and eduction passages on opposite sides of the piston.

To enable others skilled in the art to make and use my invention, I will proceed to describe its construction and operation.

A, is the cylinder which is bored truly throughout and provided, at diametrically opposite points, with slots to receive two sliding abutments, B, B which are nearly of the full length of the cylinder. It is secured to a bed-plate P, which also supports the bearings R, R, of the main shaft.

C, is the main shaft, which may be formed all in one piece with, or have rigidly attached to it in any suitable manner, the cylindrical piston head D. This cylindrical piston head has a collar E, at or near each end, which may be cast with or otherwise secured to it, said collars being at a proper distance apart to receive, between their inner faces the sliding abutments B, B, the sides of which should be packed to fit steam-tight between the collars. The collars E, E, are fitted on their peripheries with metallic packing rings a, a, which fit to the interior of the cylinder and confine the steam within the quadrangular passage F, that is formed between the piston head, the collars and the cylinder, for the piston G, to work in. The cylinder has a flanch j, bolted at each end

to overlap the collars of the piston head to prevent any longitudinal movement thereof, but otherwise, the cylinder has no heads. The piston head has a cavity b, b', in its interior whose transverse form is shown in Fig. 1, the principal portion of the said cavity being cylindrical and occupying the center of the piston head, and from this cylindrical portion, a passage c, c', leads through one side of the piston head. This cavity extends the whole length between the heads and collars E, E. The ends of the cavity b, b', and passage c, c', are grooved as shown at d, d, in Fig. 3, and the back is grooved as shown at e, in Fig. 1, to receive the ends and back edge of the piston G, which, when in the said grooves, divides the cavity c, c', b, b', into two passages c, b, and c', b', one of which constitutes a portion of the induction passage to admit steam to the piston passage F, and the other an eduction passage for the exhaustion of the steam therefrom, the former passage c, b, communicating by a narrow passage f, see Fig. 2, terminating in a groove g, made around the shaft c, outside of the cylinder, and the latter c', b', communicating by a similar passage f', terminating in a groove g', made around the shaft outside the groove g.

The two grooves g, and g', are inclosed in a stationary box H, which fits snugly around the shaft and which contains two passages i, and i', leading up to a reversing cock I, which has one passage k, see Fig. 2, leading half way around its plug to the induction steam pipe J, and another passage l, leading directly through the interior of and through one end of the plug which is to connect with the eduction steam pipe. When the cock is in the position shown in Fig. 2, the passage i, is in communication, through the passage k, with the induction pipe and the passage i', is in communication through the passage l, with the eduction pipe, consequently, c, b, f, g, i, constitute the induction passage, and c', b', f', g', i', constitute the eduction passage, but if the cock I, be moved to bring its passage k, into communication with the passage i' and its passage l, into communication with the passage i, the induction and eduction passages will be changed. By this arrangement, the steam may be admitted to either side of the piston and exhausted on the other side, at pleasure, to cause the piston head and the

main shaft to rotate in either direction and to have the direction of their rotation reversed at pleasure.

The piston G, consists simply of a plate of material with parallel faces fitted easily into the grooves d , d , and e . It has a spring h , applied to its back edge within the groove e , to force it out against the inner periphery of the piston, and other springs i^2 , i^2 , are applied to it to rest upon the outside of the piston head for the same purpose. These springs allow the piston to yield to any unevenness of the surface of the cylinder and force the piston out to compensate for wear by friction against the cylinder. The piston is kept steam tight around its sides and the back edge by the pressure of the steam upon it, which forces it up against one side of the grooves d , d , e .
 20 The sliding abutments are moved outward to allow the piston to pass them and returned again into the cylinder after the pistons pass them, by means of two grooved cams L , L , on the main shaft, outside the cylinder acting on cross heads M , M , with which the rods are connected, by rods m , working through the backs of the abutment boxes N , N . This method of operating the sliding abutment is substantially like that employed in many other rotary engines and therefore needs no further or particular description. Now in this projecting arrangement of the piston G projecting radially within or through the hollow shaft 30 or head D and passages c , c' b b' on either side of it within said head and extending the width of the piston, the admission and escape of the steam to and from the piston is uniform and rapid throughout and to or

over the whole breadth of the piston and 40 all twist or strain at either end of the piston or inequality of pressure is avoided and by the quick relief from opposing pressure which is afforded in the waste steam rapidly passing off throughout the whole 45 breadth of the piston to the exhaust, the effective power of the engine is largely increased especially where occasion requires the motion of the engine to be suddenly reversed; and the piston thus dividing the hollow head D performs the double function or use, viz, of piston and partition to form the inlet and outlet passages c c' and b b' .
 50

I do not claim the hollow shaft or piston head D with a passage or passages in its 55 periphery to admit or carry off the propelling gas or fluid as such, but with a lateral arrangement of said passages in relation to the radial piston and employing a separate transverse partition in the hollow head 60 to form inlet and outlet chambers at opposite ends of the piston, has before been used. But

What I do claim herein as new and useful in the description of rotary engines referred 65 to is—

The arrangement of the piston G projecting radially into, within or through the hollow head D, and forming inlet and outlet cavities or passages c c' and b b' on 70 either side of it across its whole breadth or face substantially as shown and described for the purposes set forth.

JNO. ROBINGSON.
